Primary Examiner — Cathron C Brooks*Assistant Examiner* — Keith Frank(74) *Attorney, Agent, or Firm* — Alston & Bird LLP(57) **CLAIM**

The ornamental design for a spout, as shown and described.

DESCRIPTION

FIG. 1 is a rear, left top perspective view of a spout according to my new design;

FIG. 2 is a left side view of the spout of FIG. 1.

FIG. 3 is a right side view of the spout of FIG. 1.

FIG. 4 is a front view of the spout of FIG. 1.

FIG. 5 is a rear view of the spout of FIG. 1.

FIG. 6 is a top view of the spout of FIG. 1.

FIG. 7 is a bottom view of the spout of FIG. 1; and,

The broken lines shown illustrate portions of the article, and environmental subject matter, and form no part of the claimed design.

1 Claim, 8 Drawing Sheets(56)
